UNITED STATES PATENT OFFICE

106,238

DESIGN FOR AN ADVERTISING DISPLAY CARD

Harry Lewy, Baltimore, Md.

Application July 27, 1937, Serial No. 70,683

Term of patent 14 years

To all whom it may concern:

Be it known that I, Harry Lewy, a citizen of the United States of America, residing at Baltimore, in the State of Maryland, have invented a new, original, and ornamental Design for an Advertising Display Card, of which the following is a specification, reference being had to the accompanying drawing, forming a part thereof,

What I claim is:—

The ornamental design for an advertising display card substantially as shown.

HARRY LEWY.
